SECURITY PARTITION FOR POLICE VEHICLES

Karl G. Feth, 4258 Elm Park Drive,
St. Louis, Mo. 63128

Filed May 27, 1968, Ser. No. 12,093

Term of patent 14 years

Int. Cl. D12—14

U.S. Cl. D14—6

FIG.1

FIG.2

FIGURE 1 is a rear perspective view of a security partition for police vehicles showing my new design.

FIGURE 2 is a front perspective view.

The automobile shown fragmentarily and in broken lines is included for illustrative purposes only.

I claim:

The ornamental design for a security partition for police vehicles as shown and described.
